UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed November 27, 1922. Serial No. 603,433.

This invention relates to signaling systems and more particularly to improved methods and means for signaling over transmission lines.

In such systems as are mentioned above, it is not unusual that considerable interference with telephone apparatus caused by the operation of associated telegraph devices and by inductive surges from neighboring power transmission lines is encountered. In some signaling systems wherein current impulses are utilized to transmit messages, a considerable factor of error may be present without materially detracting from the successful operation of the system. However, in automatic telephony, wherein current impulses are employed to operate selective mechanisms to establish telephonic connections, it is necessary that substantially one hundred per cent of the impulses transmitted be effective in operating the automatic switching apparatus in order to prevent false connections being set up.

In an automatic telephone system, let it be assumed that a set of 5, 7 and 9 current impulses are required to seize a certain line switch. If during the dialing of these impulses, the transmission line experiences an inductive surge caused by a neighboring line or by the operation of its own associated telegraph apparatus, the operating impulses may be distorted and mutilated to such an extent as to cause the false operation of telephone apparatus on the line and would possibly seize a switch other than the one originally intended for seizure, thereby setting up a false connection.

It is, therefore, an object of this invention to prevent the false operation of apparatus on a transmission line due to inductive surges.

A further object of this invention is to produce a signal indicating an unstandard condition on a transmission line.

In accordance with the above and other objects, this invention provides an electrically symmetrical circuit which under abnormal conditions and at any time during the period of sending of impulses, is adapted to operate a signal at the sending point. Further translation of the impulses through the receiving devices is also prevented.

The invention will be understood from the following description and by reference to the accompanying drawings in which Fig.

1 shows one end of an operator's cord circuit and the terminal of an outgoing line. Fig. 2 shows the receiving end of the toll line and cooperates with Fig. 1 in the description of the invention. Fig. 3 is an alternative arrangement of the receiving circuit shown in Fig. 2.

In Fig. 1, the rectangle designated by X denotes the inward equipment at station A and corresponds to the inward equipment at B which is included within the broken lines C, D in Fig. 2. The smaller rectangles T designate telegraph equipment associated with the transmission line. In Fig. 2, the line L represents any power equipment or transmission line in the neighborhood of the line P and may be considered a source of disturbance to this line.

Assuming the operator at A is called upon to send out a series of impulses from the dial 100 in order to seize the line switch associated with line relay 200, she inserts plug 101 into jack 102 and establishes a circuit extending from grounded battery 125, normal contacts of key 126, through the normal contacts of the circuit controlling elements 127 and 128 which are mounted on the armatures of relays 123 and 124, respectively, the armature and lower contacts of relay 105, the winding of the lower coil of polar relay 105, conductors 106 and 107, sleeve contacts of plug 101 and jack 102, and thence to ground through the windings of relays 108 and 109. The current flowing from battery 125 to the lower contact of relay 105 shunts winding of relay 104. This permits a second current to be traced from grounded battery 140, winding of relay 103, armature and contact of relay 104, and the upper winding of relay 105 to the sleeve conductor 106 of the circuit just traced in the path which is in parallel with the lower winding of relay 105 thereby establishing an obvious circuit for the supervisory lamp 129. Relay 105 does not operate in the circuits just traced.

Relay 109 is quick to operate, whereas relay 108 is slow operating in order that the line conductors of the line P may be connected to the 1700 cycle current source 110, before relay 108 operates. A pulse of current, the duration of which depends upon the time constants of the armatures of relays 108 and 109, is thereupon sent out over the line P by way of the armatures and back

contacts of relay 108, front contacts and armatures of relay 109, the line conductors of line P, armatures and back contacts of relays 201, 202 and 223, through the filter 203 and the primary winding of repeating coil 204. The rectifier 205 is so arranged as to rectify the alternating current induced in the secondary winding of repeating coil 204 and to permit a unidirectional current to flow 10 through the windings of relay 206 to effect its operation. Assuming the first half cycle of current to be in the direction indicated by the arrow in the primary winding of repeating coil 204, there will be a half cycle 15 of current induced in the secondary winding in the opposite direction, as indicated by the arrow, which current will traverse a path extending through the upper right-hand winding of repeating coil 204, conductor 207, winding of the upper coil of relay 208, the upper plate and filament of rectifier 205, and thence through the windings of relay 206. The second half cycle finds a path 20 through the lower right-hand winding of repeating coil 204, conductor 209, winding of the lower coil of relay 208, lower plate and filament of rectifier 205, and thence through the windings of relay 206. Relay 208 is so designed that the time constant of 25 its armature keeps the moving member normally associated therewith in engagement with the contacting element 210 during reception of alternating currents of the proper signaling frequencies.

30 Relay 206 operates and interrupts the normal energizing circuit for relay 211 which circuit may be traced from grounded battery, movable member of relay 208, contacting element 210, conductor 212, contacts of relay 206, conductor 213, and thence to ground through the winding of relay 211. Relay 211 in deenergizing retracts its armature and establishes a circuit extending from 35 grounded battery, right-hand winding of line relay 200, conductors 214, 215 and 216, winding of slow release relay 217, armature and back contact of slow-to-operate and to-release relay 218, conductor 219, back contact and armature of relay 211, windings of relay 220, conductors 221 and 222 to ground 40 through the left-hand winding of line relay 200. Upon response of relay 217, due to this circuit, its inner armature and front contact prepare a circuit for the front contact of relay 211 while the left-hand armature applies ground to energize relay 218. The response of relay 218 disconnects the 45 circuit for the back contact of relay 211 over which relay 217 first operated. The contacts of the relay 211 are preferably of the make-before-break type, so that when relay 206 restores upon cessation of the impulse of alternating current and relay 211 reoperates, it continues at its armature and front contact, the circuit through relays

200, 217 and 220. That is, relay 217 although quick to operate is slow to release, thereby retaining the circuit to the front contact of relay 211 during the movement of the armature of relay 211, and the slow 70 operating feature of relay 218 serves to delay the interruption of the original energizing circuit through relay 217 sufficiently to permit this relay to remain operated.

When the line switch associated with line 75 relay 200 is seized, a signal is transmitted back from the equipment at B to notify the operator that she may proceed to dial. The transmission of such a signal is disclosed in a patent of H. W. O'Neill, No. 1,579,236, 80 issued April 6, 1926. The alternating current flowing from the selector in sending back a signal flows over the line conductors 235 and 236, back contacts and armatures of relays 223, 202 and 201, armatures and front 85 contacts of relays 109 and 108, tip and ring contacts of jack 102 and plug 101, the outer contacts of key 111 (assuming this key to have been operated), conductors 120 and 119, conductors 117 and 118, the armatures and back contacts of relay 112, through the primary winding of the universal transformer 130. A current is thereupon induced in the secondary windings of transformer 130 of a frequency similar to that incoming 90 over the line and is rectified by the rectifier 131 and flows as a unidirectional current through the windings of relay 132. The rectifier 131 operates in a manner similar to that described in connection with the rectifier 205.

95 Relay 132 is thereupon operated and establishes a circuit extending from grounded battery, through the armature and front contact of relay 132, winding of relay 133, conductor 134, through the lower normal contacts of the dial 100, conductor 114, and thence to ground, through the outer armature and back contact of relay 115. Relay 133 is energized in the circuit just traced. 100 Upon cessation of the incoming alternating current, relay 132 becomes deenergized but relay 133 being slow to release establishes a circuit extending from grounded battery, armature and lower contacts of relay 132, 105 conductor 135, lamp 180, the armature and front contact of relay 133, and thence to ground at the outer armature and back contact of relay 115 over the energizing circuit 110 previously traced for relay 133.

115 Upon noting the illumination of lamp 180, the operator at A proceeds to operate the dial 100. The structure and operation of such dials are well known in the art and a brief description of their application to the 120 system in question will suffice to complete the description of the circuit disclosed. When the dial is operated, the transfer contacts of the dial disconnect relay 133 to extinguish lamp 180 and establish a circuit ex- 125 130

tending from grounded battery, the upper contacts of this dial, which shunt the winding of relay 112, through the resistance element 113, lower alternate contacts of the dial 100, conductor 114, and thence to ground over the back contact and outer armature of relay 115. Upon release of the dialing mechanism, the upper contacts are intermittently separated in accordance with the setting of the dial so that the shunt around relay 112 is removed a corresponding number of times. By the intermittent operation of relay 112, the 1700-cycle source 116 is alternately connected to and disconnected from the armatures of relay 112, whereupon current pulses from the source 116 are sent out over conductors 117 and 118, 119 and 120, outer contacts of key 111, tip and ring contacts of plug 101 and jack 102, front contacts and armatures of relays 108 and 109, line conductors of the line P, armatures and back contacts of relays 201, 202 and 223, through the filter amplifier 203 and the primary winding of repeating coil 204. As described in connection with the current impulse sent out from the source 110, current pulses are induced in the secondary winding of repeating coil 204 and passed through the windings of relay 208, rectifier 205 and the windings of relay 206, whereupon the latter relay is operated in accordance with the impulses.

Each time relay 206 operates, the normal energizing circuit for relay 211 is interrupted, which relay in turn intermittently interrupts through its armature and front contact an energizing circuit for line relay 200 of the switch. The slow release nature of relay 217 prevents the disconnection of the circuit at its inner front contact. Line relay 200 follows the intermittent operation of relay 211 and causes its associated switching apparatus to experience a movement to effect the desired connection.

It will now be assumed that the called subscriber has been signaled over the completed connection, and responds by the removal of the receiver from the switchhook. In removing the receiver from the switchhook, battery across the line conductors is reversed in a manner well known in the art whereupon the polar relay 220, which is bridged across the line through the armature and front contact of relay 211, front contact and inner armature of relay 217, winding of relay 217 and conductor 216, operates. Relay 220 in operating establishes a circuit extending from grounded battery, its armature and lower contact, conductors 225 and 226, lower contact of relay 227, conductor 228 to ground through the winding of relay 202. Relay 202 operates in this circuit and at its upper and middle armatures and front contacts simultaneously applies 900 and 1700 cycle currents from the sources 229 and 230

respectively, to the line conductors of line P. The currents from the sources 229 and 230 flow out over the front contacts and armatures of relay 202, back contacts and armatures of relay 201, line conductors of line P, armatures and front contacts of relays 109 and 108, tip and ring contacts of jack 102 and plug 101, normal contacts of key 111 (the key 111 having been returned to normal after dialing) conductors 121 and 122, and thence through the windings of relays 123 and 124. Relays 123 and 124 are respectively responsive to currents of 1700 and 900 cycle frequencies. Relay 202 also establishes an energizing circuit for relay 227 which may be traced from grounded battery, armature and lower contacts of relay 220, conductor 225, lower winding of relay 227, conductor 273, to ground through the front contact and armature of relay 202. Relay 227 is of the polar type and the direction of current flowing in its lower winding causes its armature to be moved from its lower to its upper contact, thereby interrupting the circuit of relay 202. This relay in restoring disconnects sources 229 and 230.

Relays 123 and 124 operate simultaneously in the circuit previously traced and at their respective circuit controlling elements 127 and 128, disconnect the battery 125 from the winding of the lower coil of relay 105. This permits the current in the winding of relay 103 and the upper coil of relay 105 to move the armature of the latter relay from its lower to its upper contact stop. On cessation of the incoming current pulse, the circuit controlling elements 127 and 128 return to normal, whereupon a circuit is established from grounded battery 125, normal contacts of key 126, normal contacts of the circuit controlling elements 127 and 128, armature and upper contact of relay 105, thence to the sleeve conductor by way of the upper winding of relay 105.

In this position of relay 105 current from battery 125 shunts the winding of relay 103 the restoration of which extinguishes lamp 129 and connects battery 140 through the winding of relay 104 and the lower winding of relay 105 to the conductor 106. The response of relay 104 disconnects relay 103 to prevent premature response of the latter relay upon the receipt of the next impulse of alternating current to disconnect battery 125. In the present condition of the circuit the greater strength of current through the upper winding of relay 105 insures that such relay will maintain its armature in engagement with its upper contact.

Assuming the period of conversation to have ended, the called subscriber replaces his receiver on the switchhook and, in so doing, again reverses the battery across the line conductors, whereupon relay 220 separates its lower and closes its upper contacts there.

4

by applying current from grounded battery over conductor 240, upper contacts and armature of relay 227, conductor 228 and thence to ground through the winding of relay 202. Relay 202 thereupon operates and at its upper and middle armatures and front contacts again connects the current sources 230 and 229 to the line conductors of line P. At its lowermost armature, relay 202 now establishes a circuit including the upper winding of relay 227, conductor 240, upper contacts of relay 220 to grounded battery at the armature of the latter relay. The direction of current through the upper winding of relay 227 causes such relay to move its armature from its upper to its lower contact stop. This deenergizes relay 202 to disconnect currents 229 and 230.

During the period in which the current sources 229 and 230 were connected to the line conductors of line P, relays 123 and 124 were actuated, as described previously and effected the illumination of supervisory lamp 129 to notify the operator that she 25 may proceed to take down the connection, and restore the apparatus to normal condition. In this instance the removal of battery from the upper contact of relay 105 permits the current in the lower winding of such relay to move its armature to its lower contact. On restoration of relays 123 and 124 the battery 125 will shunt relay 104 and the restoration of relay 104 permits relay 103 to respond in series with the upper winding of relay 105 to disconnect relay 104 and illuminate lamp 129.

Removal of plug 101 from jack 102 results in the immediate release of relay 108 to apply current from source 110 by way of the front contacts of relay 109 (still in its operated condition due to its slow-to-release characteristics). In response to this impulse of current relay 206 disconnects the relay 211 which opens the direct current loop circuit for relay 200 for an interval sufficient in duration to permit the release of relay 217 and also the release of the relays in the switches not shown, whereby the switches are restored to normal. Following the release of relay 217 and the disconnection of the slow-to-release relay 218 cessation of the alternating current impulse permits relay 206 to restore and operate relay 211, in advance of the instant when the normal contacts of relay 218 may establish the circuit through the normal contacts of relay 211. The relation of the circuit changes effected by this cycle of operation insures that the switch may not be re-seized by this incoming impulse of alternating current.

Assuming now that the key 111 is actuated and the operator is in the act of dialing and that an abnormal condition occurs on the neighboring transmission line L or from the superposed telegraph equipments, a surge

affects the transmission line P and induces currents in the secondary winding of repeating coil 204, which currents pass through the winding of relay 208 in a manner previously described. When such currents are of a nature which will pass through the filter 203 and be rectified by the device 205 a bias of polar relay 128 in one direction or another may be established. Relay 208 being designed to maintain its armature in normal condition only upon the application of relatively high frequency currents to its windings, is affected in such a manner by these currents as to cause its armature to operate in one direction or the other depending on which polarity predominates. Assuming the surge predominating to be of such polarity as to cause the armature member of relay 208 to come into engagement with the lower contact associated with the conductor 241, a circuit is established from grounded battery, armature and lower contact 242 of relay 208, conductor 241, and thence to ground through the winding of relay 223. Relay 223 thereupon operates and at its armatures and front contacts connects the 1300 cycle current source 243 to the line conductors of the line P. Current from this source flows over the armatures and front contacts of relay 223, back contacts and armatures of relays 202 and 201, armatures and front contacts of relays 109 and 108, tip and ring contacts of jack 102 and plug 101, conductors 119 and 120, 145 and 146, the filter amplifier 147, and the primary winding of transformer 148. The currents induced in the secondary windings of transformer 148 are rectified by the rectifier 149 and pass through the windings of relay 150, whereupon a circuit is established which may be traced from batteries 125 and 140, as previously traced, to conductor 106, winding of relay 115, and thence to ground through the contacts and armature of relay 150. Relay 115 thereupon energizes and establishes an obvious circuit for lamp 151 and at its inner armature and front contact completes a self-locking circuit. The operation of relay 115 also disables the dial 100 by disconnecting the ground already traced.

On noting the illumination of lamp 151, the operator is informed of the unstandard condition of the line and immediately withdraws plug 101 from jack 102, and in order to render the dial again operative and to extinguish the lamp 151, it is necessary that plug 101 be momentarily inserted in jack 160. Upon the insertion of plug 101 into jack 160, ground is placed on the sleeve conductor 107 of the cord circuit, thereby shunting relay 115 to extinguish the lamp 151 and to again connect ground to the dial 100. This disconnection will permit the complete restoration to normal of relays 108 and 109 in order that an impulse of alternating cur-

rent may be transmitted over the line to effect release of the distant switches as already described. The operator may then withdraw plug 101 from jack 160 and again inserts it into jack 102 and proceed to redial.

The jack 375 is employed in establishing a call originating at station B and the relays 376 and 201 correspond to and function in a manner similar to relays 108 and 109, respectively. When the line P is in use from the point A, a busy condition may be established at this jack 375 in the same manner as that employed in the copending application of O'Neill, Serial No. 586,616, filed September 7, 1922.

The arrangement shown in Fig. 3 provides a normally balanced circuit adapted to be non-responsive to every other half cycle of incoming current and to utilize only half cycles of the same polarity to operate the associated switching apparatus.

The direction of the effective half cycles of current is indicated on the drawing by the arrows and the current induced in the upper winding of the secondary of repeating coil 304 traverses a path through the upper right-hand winding of repeating coil 304, upper coil of relay 306, plate and filament of rectifier 301, upper coil of relay 308, conductor 317 and back through the upper winding of the secondary of repeating coil 304. The current induced by the same half waves in the lower secondary winding of repeating coil 304 flows from the mid-point of the secondary winding through the lower coil thereof, conductor 309, lower coil of relay 308, the plate and filament of rectifier 305, the lower winding of relay 306 and back to the mid-point of the secondary winding of repeating coil 304. The windings of relay 308 are so proportioned and the lower winding thereof resonated by the condenser 302 that under the regular operating frequency of the line, relay 306 does not operate whereas relay 308 does operate and interrupts the normal energizing circuit for relay 311. The dissimilar windings of relay 308, due to condenser 302, present like impedances with respect to the differential paths through relay 306 at the frequency employed for dialing. In the event that currents of a different frequency reach the circuits of relays 306 and 308, a non-symmetrical impedance condition will result in the response of relay 306 to engage its contacts. Before the break signal relay 223 may be operated, however, it is necessary for line relay 308 to also be operated in order that grounded battery may be supplied through the contacts of relay 306. The circuit for relay 311 may be traced from grounded battery through the armature and lower contact of relay 308 and conductor 313 to ground through the

winding of relay 311. Relay 311 functions in a manner similar to that of relay 211 described in connection with Fig. 2.

If in establishing a connection the distant switches encounter a trunk or line busy condition, alternating currents may be transmitted back over the line and the dialing signal lamp 180 or the supervisory lamp 129 illuminated, depending upon the position of key 111.

Signal 180 is adapted to respond when a "path's busy" or a "line busy" condition is encountered by the distant switching devices during the establishing of a connection. Impulses of alternating current may then be sent back over the toll line in the same manner as is employed in the copending application of O'Neill, Serial No. 586,616, filed September 7, 1922. A first response of the relay 132 serves to energize relay 133, and subsequent incoming impulses in operating relay 132 will cause the lamp 180 to be flashed in one characteristic manner for "path's busy" condition and in another characteristic manner for a "line busy" condition, as is well understood in the art.

In case busy signals are returned subsequent to the restoring of key 111, the supervisory lamp 129 will be correspondingly operated. The key 126 is for the purpose of permitting the operator to reverse any given condition of the lamp 129. If the lamp is lighted, momentary operation of the key will cause it to be extinguished and if the lamp is extinguished, momentary operation of the key will cause it to be lighted.

Further supervisory service may be rendered by the signal 180, for example, in the event that dialing key 111 is not restored sufficiently soon after the completion of dialing operation. The response of a called subscriber and the resulting impulse of alternating currents from the sources 229 and 230 as already described will effect lighting of the lamp 180. Also in the event that the called subscriber resorts to flashing, that is, moves his switchhook to call the operator, the resulting impulses of alternating current will cause lamp 180 to be extinguished each time the relay 132 responds and lighted each time it is released.

What is claimed is:

1. In a switching system, a line, means for transmitting high frequency alternating current impulses, a signal, and means for operating said signal actuated during the transmission of said impulses upon the establishment of electrical conditions on the line other than said impulses.

2. In a switching system, a line, means for transmitting high frequency alternating current impulses, a signal, and means for operating said signal and disabling the

transmitting means actuated during the transmission of said impulses upon the establishment of electrical conditions on the line other than said impulses.

5. In a switching system, a line, means for transmitting high frequency alternating current impulses over said line, means responsive to said impulses for translating the same into direct current impulses for 10 switching purposes, a signal, and means operative to actuate said signal upon the establishment of electrical conditions on the line other than said impulses.

4. In a switching system, a line, means for 15 transmitting high frequency current impulses over said line, means responsive to said impulses for translating the same into direct current impulses for switching purposes, a signal, means operative upon the 20 establishment of electrical conditions other than said alternating current impulses to disable the impulse responsive means, and means operative to actuate said signal when said impulse responsive means is disabled.

25. 5. In a switching system, a line, means for transmitting high frequency current impulses over said line, means responsive to said impulses for translating the same into direct current impulses for switching purposes, a signal associated with said line, a 30 source of high frequency alternating cur-

rent, means for disabling the impulse responsive means operative upon the establishment of any electrical conditions on the line other than the impulse produced by the 35 transmitting means, means for connecting said source of high frequency alternating current to the line operative when the impulse responsive means is disabled, and means responsive to current from said source 40 when connected to the line for operating said signal.

6. In a signaling system, a transmitting medium, means for transmitting high frequency alternating currents over said medium, switching means responsive to currents other than said high frequency currents present on said transmitting medium for disabling said transmitting means.

7. In a signaling system, a transmitting 50 medium, means for transmitting high frequency alternating currents over said medium, a signal, switching means responsive to currents other than said high frequency alternating currents present on said transmission medium for disabling said transmitting means and for operating said signal.

In witness whereof, I hereunto subscribe my name this 17th day of November A. D. 1922.

HENRY W. O'NEILL.
